UNITED STATES PATENT OFFICE.

ALEXANDER CLAPPERTON, OF YONKERS, NEW YORK, ASSIGNOR TO AMERICAN WARP DRAWING MACHINE COMPANY, A CORPORATION OF MAINE.

MECHANISM FOR HANDLING TUFT-YARNS FOR CARPET-LOOMS.

1,235,654.

Specification of Letters Patent.

Patented Aug. 7, 1917.

Application filed April 26, 1910, Serial No. 557,706. Renewed December 29, 1916. Serial No. 139,705.

To all whom it may concern:

Be it known that I, ALEXANDER CLAPPERTON, a citizen of the United States, residing at Yonkers, in the county of Westchester and State of New York, have invented an Improvement in Mechanism for Handling Tuft-Yarns for Carpet-Looms, of which the following description, in connection with the accompanying drawings, is a specification, like letters on the drawings representing like parts.

This invention relates to mechanism for handling tuft yarns for carpet looms.

In order that the principle thereof may be readily understood, I have disclosed a single embodiment thereof in the accompanying drawings, wherein—

Figure 1 is a perspective view of a portion of a yarn tufting mechanism embodying my invention;

Fig. 2 is a detail in vertical section representing one manner of controlling the reciprocatory movements of the yarn tube carriage;

Fig. 3 is a plan view of a portion of the clamp preferably used in the practice of my invention;

Fig. 4 is a detail in vertical section taken through the yarn tube carriage and clamp;

Fig. 5 is a detail representing the shifted or shogged position of the clamp with reference to the needles;

Fig. 6 is a side elevation partially in vertical section of the mechanism shown in Fig. 1;

Fig. 7 is a side elevation of a slightly modified form of mechanism embodying my invention; and

Fig. 8 is a plan view, partially broken away, of such modified form of my invention.

My invention comprehends an improved apparatus for drawing tuft yarns into and through the tubes or carriers of a usual tube frame employed to place such yarns in the sheds formed by the warps of a loom during the weaving process.

Referring more particularly to that form of my invention shown in Figs. 1 to 6, the base or support for the mechanism is repre-

sented at 1, it being provided with a suitable number of guide rails, one of which is indicated at 2. Preferably two guide rails are employed, one at each side of the apparatus. In the present embodiment of my invention I employ a number of tubes or carriers corresponding to the number of tuft yarns to be drawn, and as herein shown I employ one half as many needles as tubes, it being evident, however, that any suitable number of needles may be used. A relative longitudinal movement is imparted to the needles and tubes, and herein I have represented the tubes as reciprocated and the needles as stationary. The needles are represented at 3 in Figs. 4 and 6 and are therein shown as horizontally supported upon a suitable bed 4 preferably fixedly secured to the base. The needles may have the usual hooked ends 5. Supported upon and movable longitudinally along guide rails 2 is a tube carriage 6 having mounted thereon a suitable number of tubes or carriers 7 of any suitable construction.

In order to provide for the to and fro movement of the tube carriage with respect to the needles 3, I have in this type of my invention represented the rails 2 as suitably grooved. In Fig. 1, I have shown one of the rails as provided in its upper face with a groove 8, which for a portion of its length has a longitudinal tongue 9, thus dividing such portion of the groove into parallel grooves 10, 11, the tongue terminating at the point 12.

Rising from the carriage 6 are uprights 13 supporting the yarn beam 14 carrying the usual yarns 15. Preferably these yarns are leased or divided into a plurality of and preferably two sheds, and are so supported as to permit the drawing of the yarns into the tubes in the desired order.

Herein I have represented the yarns 15 as divided into two sheds or banks 16, 17, and have shown a suitable clamp receiving the yarn ends. While this clamp may be of any suitable construction, it is here shown as composed of two outer bars 18—18 and an intermediate and preferably grooved bar 19, the yarns 16 and 17 being clamped in position.

sition between said bars with suitable pressure. If desired, one of the outer bars may be removed from clamping position after the yarns pertaining thereto have been seized by the needles 3 so as to permit the 5 yarns to be drawn through the tubes, or if preferred the clamping members may hold the yarns so loosely as to permit the yarn ends to be drawn from the clamp upon return movement of the needles. To this latter end, one or more of these bars may be faced with textile or other suitable material, providing a yielding grip for the yarns.

The yarn tubes or carriers 7 are removably positioned upon the carriage 6 and may be suitably held or supported in operative position with respect to the needles. To that end, I have, in Figs. 1 and 6, represented a horizontally positioned bar 20 having therein cam slots 21 receiving pins or screws 22, by which said bar is supported upon the uprights 13 over the tubes or carriers 7. When the bar is in the position shown in Figs. 1 and 6, its lower and preferably smooth edge rests upon the tubes or carriers and holds them in position. When, however, it is moved toward the right, viewing Fig. 1, it is elevated therefrom so as to permit the removal or further adjustment 25 of said tubes or carriers.

The yarn beam 14 is mounted in a suitable support, herein shown as sockets 24 receiving the heads of said beam, said sockets each having preferably pivoted thereto a jaw 25 held in frictional engagement with the adjacent flange of the yarn beam by coil spring 26. Any suitable type of beam support may, however, be employed.

The beam support, whatever the type 40 used, is preferably tensioned so as to permit the same to yield slightly toward the needles and tubes, and to return to normal position when the strain upon the yarns ceases. To this end, each socket is pivoted 45 as at 27 upon the uprights 13 and springs 28, and straps 29 connect said uprights and sockets so as normally to maintain the yarn beam in its more remote position with respect to the needles but permitting it to 50 yield as an entirety when the needles and tubes are operated to thread the latter. I preferably provide set screw 29' constituting adjustable stops limiting the return movement of said sockets 24.

I have herein represented the tube carriage 6 as provided with tongues 30 received in the grooves 8 of the guiding rails. These tongues 30 are of such thickness as to permit them to slide in either groove 10 or 11, as 60 most clearly indicated in Fig. 1.

Inasmuch as in this type of my invention there are one half as many needles as yarn tubes, the needles and tubes are so positioned that the needles are in alinement with alternate tubes as well as with either the yarns

16 or the yarns 17. Assuming that the yarns 16 are first to be drawn through the tubes or carriers 7, the carriage 6 is slid to the left, viewing Fig. 1, until the tongues 30 thereof may be slid into the grooves 11 of the rail guides 2. This brings the needles 3 into alinement with alternate yarn tubes and with the shed of yarns 16. In other words the alternate yarn tubes referred to constitute a set or plurality in substantial alinement with which one of the yarn sheds is held clamped while the other yarn shed is held out of alinement therewith. Thereupon the tube carriage is moved to the left, viewing Fig. 6, this being accomplished by hand, to which end the carriage is provided with suitable handles 31. When by movement of the carriage, the yarns and needles are brought into substantially the relation indicated in Fig. 4, the clamp members 18, 19 are slid by hand to the right or to the left, so as partially to envelop the needles by the yarns and bring the yarns and needles into substantially the relation indicated in Fig. 5. This insures the engagement of the yarns by the hooks 5 of the needles when the latter are withdrawn through the tubes upon the return movement of the carriage 6.

If desired, I may provide suitable means coöperating with the member 4 to support the needles in their proper position. To this end, I have shown a horizontal plate 32 having a notched, down turned, flange 33 engaging the needles, the said plate being supported from preferably a plurality of rods 34 mounted in brackets 35, 36 carried by said plate 32 and the member 4. I may employ two rods, one adjacent each side of the mechanism. Encircling each rod is a spring 37. Each rod 34 passes loosely through its bracket 36 and is headed at 38 exteriorly thereof. The springs 37 normally project the rods to the right as indicated in Fig. 6, and hence yieldingly project the needle positioning plate 32. Upon movement of the tube carriage 6 toward the left, viewing said figure, the plate 32 is moved toward the left by the carriage, thereby compressing the springs 37 and projecting the rods through said brackets 36. When the yarn tube carriage is moved toward the right, viewing said figure, the plate 32 is returned to the position shown in Fig. 6.

After one shed of yarns, which may be either the yarns 16 or 17, has been threaded through the proper yarn tubes 7, the carriage 6 is again reciprocated so that the yarns of the remaining shed are drawn through the remaining tubes. Upon such second reciprocation, the tongues 30 of the tube carriage 6 are slid in the grooves 10, thus bringing the needles into alinement with the remaining half of the tubes through which the yarns had not previously been drawn. It is apparent that a different

length of stroke is imparted to the carriage for drawing the two sheds of yarns, and to this end suitable stops may be provided to limit the differential movements of the carriage. In this embodiment of my invention, the carriage is reciprocated by hand and the clamp is, similarly, slid transversely of the carriage by hand.

In the event that a less number of needles than tubes or carriers is used, I may align the needles with those in which the tuft yarns are to be drawn by any single operation, by aligning movement of the needles rather than of the tubes. In Figs. 1 to 6 inclusive, I have illustrated one form of means for laterally shifting the tubes with respect to the needles. In Figs. 7 and 8, I illustrate one form of means for moving the needles laterally with respect to the tubes or carriers, in order to align them with those tubes through which the tuft yarns are next to be drawn. It will be understood, however, that any suitable aligning means may be employed. In said figures, I have represented substantially the same construction of tube carriage 6 mounted for sliding movement upon the guide rails 2, which, however, are not provided with the divided or tongued grooves, but each with a single groove compelling reciprocatory movement of said carriage always in the same path. The needles 3 are mounted in a preferably notched plate 39 mounted for sliding movement upon the upper faces of blocks 40, 40 secured to the guide rails 2. Screws 41 passing through elongated slots 42 in the plates 39 maintain the latter in position but permit their movement to the right or left to align the needles with the tubes or carriers. Surmounting the needles 3 is a plate 43 secured by screws 44 or otherwise to the plate 39 and holding the needles in position.

Any suitable means may be provided to move the plate 39 with the needles to the right or left for the purpose stated. Herein I have represented the right hand edge of said plate 39 as beveled rearwardly at 45. With said beveled edge engages the inclined face 46 of a wedge 47 mounted for sliding movement upon the upper face of one of the blocks 40 and guided in such movement by a pin and slot 48 and block 49. It will be apparent that the plate 39 and needles 3 are moved to the left viewing Fig. 8 by the wedge 47. To return said plate and needles upon movement of said wedge to the rear, viewing Fig. 8, I preferably provide a spring 50 positioned between the left hand block 40 and a lug or projection 51 upon the under side of the plate 39. It will be understood that if desired positive means may be employed to move the plate 49 in both directions. In order to reciprocate the wedge 47, I may employ any suitable mechanism. Herein for the purpose I have represented

a cam disk 52 pivoted at 53 upon one of the side rails 2 and provided with a cam track 54. Co-axial and fast with the cam disk 52 is a four toothed ratchet 55, with which is adapted to engage a pawl 56 pivotally or otherwise suitably secured upon the carriage 6 and herein represented as adjustable by set screw 57. The cam track 54 is substantially elliptical in shape and receives therein a pin 58 carried by a rod 59, to the opposite end whereof is pivoted at 60 a lever 61 pivoted at 62 upon the framing and connected by pin and slot 63 to the wedge 47. It will be apparent that upon movement of the carriage 6 toward the right viewing Fig. 7, the pawl 56 will engage the ratchet 55 and turn the cam disk 52 ninety degrees. The contour of the cam track 54 is such as to thereby compel movement of the rod 59 to the right, viewing said figure, and thereby to move the wedge 47 in the opposite direction and permit the spring 50 to force the needles 3 and plate 37 toward the wedge 47 for the purpose stated. A further movement of the cam disk 52 through a distance of ninety degrees will project the rod 59 in the opposite direction or to the left viewing Fig. 7, and return the wedge 47 to the position shown in Fig. 8, thereby forcing the needles 3 and plate 37 in the opposite direction.

In order to move the cam disk 52 as described, it is merely necessary to slide the yarn carriage 6 by hand a sufficient distance to the right, viewing Fig. 7. When in this manner the cam disk 52 has been moved a proper distance and the needles have thereby been shifted to the right or left and brought into alignment with the proper tubes or carriers 7, then the carriage 6 is moved along the guide rails 2 in the opposite direction, in order to compel the needles 3 to pass through said tubes or carriers and to engage the yarns 16 or 17 as the case may be.

Having thus described one illustrative embodiment of my invention, I desire it to be understood that although specific terms are employed, they are used in a generic and descriptive sense and not for purposes of limitation, the scope of the invention being set forth in the following claims.

Claims.

1. Mechanism for tubing tuft yarns in carpet manufacture comprising in combination, a tube frame support, threading needles co-operating therewith, and means to support the tuft yarns in sheds in operative relation to said tubes or carriers and needles.

2. Mechanism for tubing tuft yarns in carpet manufacture comprising in combination, a tube frame support, and means to support tuft yarns in sheds adjacent the mouths of said tubes.

3. Mechanism for tubing tuft yarns in carpet manufacture including a tube frame

- support, a plurality of threading needles and a tuft yarn clamp, said clamp and support being together relatively movable transversely of the needles.
5. Mechanism for tubing tuft yarns in carpet manufacture comprising tubes or carriers, and means to clamp the yarn in sheds adjacent thereto and including the clamping members 18 and 19.
10. Mechanism for tubing tuft yarns in carpet manufacture comprising threading needles, a carriage movable toward the needles, yarn tubes on said carriage and a tuft yarn clamp supported upon the carriage.
15. Mechanism for tubing tuft yarns in carpet manufacture comprising yarn tubes or carriers, threading needles, and a tuft yarn clamp movable toward and from the needles and transversely thereof.
20. Mechanism for tubing tuft yarns in carpet manufacture comprising in combination yarn tubes or carriers, threading means therefor, and means releasably to hold the tuft yarns in sheds in position to be drawn through said tubes or carriage.
25. A clamp for use in mechanism for holding tuft yarns in leased condition in carpet manufacture and comprising a clamp member 19 having opposite grooved edges and clamping members 18 coöperating therewith.
30. Mechanism for tubing tuft yarns in carpet manufacture comprising in combination, yarn threading means, and a tuft yarn spool bodily movable toward and from said threading means.
35. Mechanism for tubing tuft yarns in carpet manufacture comprising in combination, threading means, a yarn spool support, and spring means permitting the bodily movement of said support toward said threading means.
40. Mechanism for tubing tuft yarns in carpet manufacture comprising in combination a plurality of yarn tubes or carriers, a plurality of threading needles coöperating therewith but less in number than said yarn tubes, means for imparting successive threading movements to said plurality of needles, and means for shifting the relation of the needles and the tubes between successive threadings.
45. Mechanism for tubing tuft yarns in carpet manufacture comprising in combination a plurality of yarn tubes and carriers and a plurality of threading needles co-operating therewith but less in number than said yarn tubes, means to impart a threading movement to the needles, and means to aline the needles with successive groups of said tubes less than the entire number of the latter, whereby said groups are threaded in succession.
50. Mechanism for tubing tuft yarns in carpet manufacture comprising in combination a plurality of yarn tubes or carriers, a plurality of threading needles equal in number to one-half of said tubes, means to impart a threading movement to said plurality of needles, and means to aline said needles first with one half of the tubes and then with the remaining half thereof.
55. Mechanism for tubing tuft yarns in carpet manufacture comprising in combination a plurality of yarn tubes, a plurality of threading needles less in number than the tubes, and means to aline said needles with a plurality of tubes less than the entire number of the latter, and then to aline said needles with the remaining tubes.
60. Mechanism for tubing tuft yarns in carpet manufacture comprising in combination a plurality of yarn tubes and a plurality of threading needles equal in number to one-half of said tubes, means to impart a threading movement to said plurality of needles, and means to aline the needles first with one half of the tubes and then with the remaining half thereof.
65. Mechanism for tubing tuft yarns in carpet manufacture comprising in combination a plurality of yarn tubes, a plurality of needles less in number than the entire number of tubes, and means to clamp the tuft yarns in sheds adjacent the mouths of said tubes.
70. Mechanism for tubing tuft yarns in carpet manufacture comprising in combination a plurality of yarn tubes, a plurality of needles less in number than the entire number of tubes, and means to aline the needles first with one half of the tubes and then with the remaining half thereof.
75. Mechanism for tubing tuft yarns in carpet manufacture comprising in combination means to clamp the tuft yarns in a pair of sheds, one of said sheds having its yarns in substantial alinement with certain predetermined tubes of a tube frame and the other shed having its yarns transversely out of alinement with the same tubes.
80. Mechanism for tubing tuft yarns in carpet manufacture comprising in combination, yarn tubes or carriers, means to position the tuft yarns in a pair of sheds operatively related to said tubes or carriers and threading needles, the tubes or carriers and needles being relatively movable toward each other, and means for effecting alternate, relative threading movements of different lengths of said tubes and needles.
85. Mechanism for tubing tuft yarns in carpet manufacture comprising in combination, yarn tubes or carriers, means to position the tuft yarns in a pair of sheds adjacent said tubes, and means whereby said carriage may be moved in different paths toward and from said needles.
90. Mechanism for tubing tuft yarns in carpet manufacture comprising in combination, threading needles, a carriage, yarn tubes upon said carriage, means upon said carriage to position the yarns in sheds adjacent said tubes, and means whereby said carriage may be moved in different paths toward and from said needles.
95. Mechanism for tubing tuft yarns in carpet manufacture comprising in combination, threading needles, tubes or carriers reciprocal with respect to the needles, and means to position the tuft yarns in a plurality of sheds adjacent said tubes or carriers, said tubes or carriers having threading movements of varying lengths.
100. Mechanism for tubing tuft yarns in carpet manufacture comprising in combination, yarn tubes or carriers, threading means therefor, a yielding support for the tuft yarn spool, and means to position the free ends of said yarns in a plurality of sheds.
105. Mechanism for tubing tuft yarns in carpet manufacture comprising in combination, a plurality of yarn tubes or carriers, 110
110. Mechanism for tubing tuft yarns in carpet manufacture comprising in combination, threading needles, tubes or carriers reciprocal with respect to the needles, and means to position the tuft yarns in a plurality of sheds adjacent said tubes or carriers, said tubes or carriers having threading movements of varying lengths.
115. Mechanism for tubing tuft yarns in carpet manufacture comprising in combination, threading needles, tubes or carriers reciprocal with respect to the needles, and means to position the tuft yarns in a plurality of sheds adjacent said tubes or carriers, said tubes or carriers having threading movements of varying lengths.
120. Mechanism for tubing tuft yarns in carpet manufacture comprising in combination, yarn tubes or carriers, threading means therefor, a yielding support for the tuft yarn spool, and means to position the free ends of said yarns in a plurality of sheds.
125. Mechanism for tubing tuft yarns in carpet manufacture comprising in combination, a plurality of yarn tubes or carriers, 130

- threading means therefor, a yarn spool support bodily yieldingly mounted and a clamp to position the free ends of the tuft yarns in a plurality of sheds. 5
22. Mechanism for tubing tuft yarns in carpet manufacture comprising in combination, a support having guide rails, a carriage mounted upon said rails, yarn tubes, and a yarn clamp mounted upon said carriage, and threading means co-operating with said tubes or carriers, said carriage being movable toward and from said threading means. 10
23. Mechanism for tubing tuft yarns in carpet manufacture comprising in combination, a tube frame support, a series of threading needles having hooked ends, and a tuft yarn clamp to support the yarns adjacent said tubes, said clamp and tubes being movable transversely of said needle hooks. 15
24. Mechanism for tubing tuft yarns in carpet manufacture comprising in combination a tube frame support, a plurality of threading means and tube frame support having a movement toward and from each other at one time in one path and at another time in a different path. 20
25. Mechanism for tubing tuft yarns in carpet manufacture comprising in combination a plurality of yarn tubes or carriers, a plurality of threading means, said tubes or carriers and threading means having a movement toward or from each other at one time in one path and at another time in a different path, and means for supporting tuft yarns in a plurality of sheds adjacent the tubes or carriers. 30
26. Mechanism for tubing tuft yarns in carpet manufacture comprising in combination, tubes or carriers, threading needles therefor, fixedly positioned means for supporting the bases of said needles, and positioning means for said needles between said support and their free ends. 40
27. Mechanism for tubing tuft yarns in carpet manufacture comprising in combination needles 3 having hooked ends 5, a fixed support 4 for said needles, and a plate 32 engaging said needles between the support 4 and hooked ends 5. 45
28. Mechanism for tubing tuft yarns in carpet manufacture comprising in combination, a carriage having tubes or carriers mounted thereon, threading needles 3 having hooked ends 5, a fixed support 4 for said needles, and a yielding guide 32 engaging said needles near their hooked ends. 55
29. An alining guide or clamp for tuft yarns comprising a main body piece and means to clamp the yarns in engagement with the said body piece and in a plurality of sheets or sheds. 60
30. An alining clamp for tuft yarns comprising a main body piece adapted to receive the yarns in a plurality of sheets or
- sheds and separate means to clamp each sheet or shed in engagement with the said body piece. 65
31. In apparatus for drawing tuft yarns into tube frames, in combination, means to support a tube frame of a given density of tubes per inch, a series of co-acting needles of a less density per inch, and devices to guide the needles in successive tube drawing-in movements through successive independent series of the tubes. 70
32. In apparatus for drawing tuft yarns into tube frames, in combination, means to support a tube frame of a given density of tubes per inch, a series of co-acting needles of a less density per inch, and automatic devices to guide and pass the drawing-in needles in successive drawing-in movements through successive independent series of the tubes. 75
33. In apparatus for drawing tuft yarns into tube frames, in combination, devices to support tuft yarns in related or independent sheets or sheds, means to support a tube frame of a given density of tubes per inch, a series of co-acting needles of a less density per inch, and devices to guide the said co-acting needles in successive drawing-in movements through successive independent series of the tubes whereby successive sheets or sheds of threads are drawn in through said tube frame at successive needle operations. 80
34. In apparatus for drawing tuft yarns into tube frames, in combination, devices to support tuft yarns in related or independent sheets or sheds, means to support a tube frame of a given density of tubes per inch, a series of co-acting needles of a less density per inch, and devices to guide the said co-acting needles in successive drawing-in movements through successive independent series of the tubes whereby successive sheets or sheds of threads are drawn in through said tube frame at successive needle operations, the said tuft yarn supporting devices being mounted to permit movement transverse of the needles to cause an engagement of the latter with the respective yarns. 85
35. In an apparatus for tubing tuft yarns in carpet manufacture, the combination with a fixed series of needles, of a tube frame support, means for moving the tube frame support toward the needles, and guiding or alining means for the forward ends of the needles adapted to retract with the advancement of the tube frame support. 90
36. In an apparatus for tubing tuft yarns in carpet manufacture, the combination with a fixed series of needles of a tube frame support movable toward and from the needles and guiding and alining means for the needles. 100
37. In an apparatus for tubing tuft yarns in carpet manufacture the combination with

a fixed series of needles of a tube frame support movable toward and from the needles.

38. In an apparatus for tubing tuft yarns in carpet manufacture, the combination with 5 a clamp for holding said yarns in a plurality of sheds, of means for tubing the respective sheds in succession.

39. In an apparatus for tubing tuft yarns the combination with a clamp adapted to 10 clamp the yarns in a plurality of sheds, of a tube frame support and threading means

adapted to engage and tube first the yarns of one shed and subsequently the yarns of the other shed.

In testimony whereof, I have signed my 15 name to this specification, in the presence of two subscribing witnesses.

ALEXANDER CLAPPERTON.
